RIDING MOWER GRASS CATCHING BAG

Victor Leader, Minneapolis, Minn., assignor to Leader Farms, Inc., Minneapolis, Minn., a corporation of Minnesota

Filed Jan. 11, 1968, Ser. No. 10,123

Term of patent 14 years

(Cl. D40—1)

FIGURE 1 is a perspective view of the riding mower grass catching bag;

FIGURE 2 is a top view;

FIGURE 3 is a side view of the outside of the bag;

FIGURE 4 is a front view; and

FIGURE 5 is a rear end view.

The broken line skid, arms and mount in FIGURES 1 and 2 are shown merely to illustrate the support structure for attaching the grass catching bag to the riding mower.

I claim:

The ornamental design for a riding mower grass catching bag, substantially as shown and described.
